UNITED STATES PATENT OFFICE.

CHARLES L. BUEKER, OF BROOKVILLE, KANSAS.

STRAW-SPREADER.

1,244,288.

Specification of Letters Patent. Patented Oct. 23, 1917.

Application filed February 24, 1917. Serial No. 150,738.

To all whom it may concern:

Be it known that I, CHARLES L. BUEKER, a citizen of the United States, residing at Brookville, in the county of Saline and State 5 of Kansas, have invented certain new and useful Improvements in Straw-Spreaders, of which the following is a specification.

This invention relates to apparatus for spreading straw upon a field for the purpose 10 of fertilizing the ground and the object of the invention is to provide a machine in which a large quantity of the decomposed straw may be carried and by which the straw will be effectually spread in rear of 15 the machine as the same is drawn over the field.

The invention is illustrated in the accompanying drawings and resides in certain novel features which will be first fully de- 20 scribed and then particularly pointed out in the appended claims.

In the drawings,

Figure 1 is a perspective view of my im- 25 proved apparatus, the frame or inclosing rack being indicated in dotted lines and the mechanism for conveying the straw to the rear end of the machine and delivering it to the spreaders being shown in full lines;

Fig. 2 is a plan view of the improved 30 mechanism;

Fig. 3 is a rear elevation of the machine with parts broken away and in section;

Fig. 4 is an enlarged longitudinal section.

In carrying out my invention, I employ 35 two main sills 1 which converge toward their front ends and have said ends secured to a bolster 2 which is supported through a fifth-wheel 3 and a king bolt 4 upon the front axle 5, a draft-pole or tongue 6 ex- 40 tending from said front axle so that draft animals may be readily harnessed to the machine to draw the same over the field. Braces 7 are secured at their rear ends to the sills 1 and have their front ends fitted upon 45 the lower end of the king bolt 4 and are held against dropping therefrom by a cot- 50 ter-pin or nut, or other device, as will be readily understood. The front end of the truck or supporting frame is thus effectu- 55 ally braced and mounted upon the front axle so that collapse of the forward portion of the apparatus will be unlikely and the ma- chine may be easily steered.

Cross bars 8 are secured upon the side 55 sills 1 at intervals and project laterally beyond both sills. A floor or deck 9 is

secured upon these cross bars and sides 10 of any preferred construction are built upon the floor or deck and the projecting ends of the cross bars, it being thereby possible to 60 load the rack with a large quantity of straw and prevent loss of the straw by the same falling over the sides of the truck. The rear portion of the truck is supported by a 65 rear axle 11 upon which ground wheels 12 are mounted, these wheels being preferably loose upon the axle but connected with the same by the well-known escapement ratch- 70 ets so that rearward movement of the wheels will not affect the operating mechanism while forward movement of the wheels will 75 actuate said mechanism.

Upon the axle 11, at about the center of the same, is mounted a sprocket wheel 13 which is loose upon the axle but is held 80 against longitudinal movement thereon and one end of the hub 14 of this sprocket wheel is constructed with notches, as shown at 15, whereby said hub constitutes a clutch mem- 85 ber. The opposite end of the hub is con- 90 structed with an annular rib or flange, indicated at 16, and over the said rib or flange are fitted the internally grooved ends of the clamping members 17 which are bolted se- 95 curely upon the axle so that they will be 100 constrained to rotate with the axle and held against longitudinal movement thereon. The clamp members, obviously, due to their engagement with the rib or flanged end of the hub of the sprocket wheel, will hold the 105 said sprocket wheel against movement along the axle. A clutch member 18 is mounted upon the axle and constructed to engage the notched end of the hub of the sprocket wheel, as shown in Fig. 3, so that rotation 110 of the axle may be imparted to the sprocket wheel. This clutch member 18 is slideable upon the axle and is held to the same by a key or feather, as shown at 19 in Fig. 3, and it is externally grooved to facilitate its en- 115 gagement by a yoke 20 on the rear end of an angle lever 21 which is fulcrumed upon a cross bar of the truck. The front end of the angle lever is connected by a link 22 with the lower end of a hand lever 23 mounted 120 upon the front end of the truck in any con- 125 venient or preferred manner and equipped with the usual latch 24 engaging a holding segment 25 whereby it will be maintained 130 in any position in which it may be set. It 135 will be readily understood that by causing the rear end of the angle lever 21 to swing

toward the adjacent side of the truck, the clutch will be withdrawn from its engagement with the sprocket wheel hub and the rotation of the axle will not then affect the sprocket and the mechanism will remain at rest. If the lever be swung in the opposite direction, the clutch will be thrown into engagement with the sprocket wheel hub and all the mechanism will then be set in motion. A counter-shaft 26 is journaled in suitable bearings upon the sills 1 and at the center of this shaft is a sprocket wheel 27 which bears upon and engages the upper run of a sprocket chain 28 which is trained around the main driving sprocket 13 and a sprocket 29 on the shaft 30 through which motion is imparted to the spreader reels. Near one end of the shaft 26, I secure thereto a sprocket pinion 31 around which is trained a chain 32, said chain being also passed around a sprocket 33 fixed upon a shaft 34 which is journaled in suitable bearings upon the rear uprights 35. The uprights 35, as shown most clearly in Fig. 3, define a discharge opening and the shaft 34 extends across the lower portion of said opening and carries a pair of rollers or wheels 36 which partly support and impart motion to the conveyer consisting of the chains 37 and the cross bars 38 secured to said chains. The forward end of the conveyer is carried by sprocket pinions 39 secured upon a shaft 40 mounted in suitable bearings on the sills 1 below the deck or floor 9 so that the forward portion of the conveyer will be below the bottom of the load and, therefore, will easily take up the straw and draw the same to the rear end of the machine. It will be readily understood that the sprocket chain 28, acting upon the pinion 27, rotates the shaft 26 and the rotation of said shaft is transmitted through the sprocket 31 and chain 32 to sprocket 33 and shaft 34 and said shaft acts directly upon the conveyer so that the upper run of the conveyer will travel toward the rear of the machine. The rear ends of the sills 1 project beyond the uprights 35 and the rear end of the rack and upon the said projecting ends, I secure flooring 41 to prevent the straw discharged from the rack by the conveyer dropping at once to the ground or falling upon and clogging the action of the shaft 30 and the parts connected therewith. Around the ends of the sill 1, I secure a frame 42 which consists of a bar of metal extending over the upper edges of the sills and having its ends turned down against and secured to the outer sides of the sills, and a second bar extending between the lower ends of the first-mentioned bar and having its extremities secured rigidly thereto. At intermediate points of this frame, between the sills, I provide uprights 43 which are secured rigidly to the top and bottom members of the frame, and the shaft

30 is journaled in bearings secured to these uprights. The ends of the said shaft are equipped with beveled gears 44 which mesh with beveled pinions 45 on the spreader shafts 46, the said spreader shafts being journaled in bearings provided upon the top of the frame and extending above the deck 41. To the upper ends of the spreader shafts, I secure heads or brackets 47 and upon the upper ends or sides of these heads or brackets, I rigidly secure a plurality of spreader arms 48, the said arms being preferably constructed of angle iron so that they will readily beat against the falling straw and throw the same laterally from the machine. To each of the arms 48, I secure a tooth or shredding plate 49 which will take into the straw and cut through the same so that when it is thrown from the machine it will be in very small particles. The spreader shafts pass through both the top and bottom of the frame 42 and are thereby very effectually supported so as to resist torsional strain and as the bottom bar of this frame is removable the parts may be readily assembled or the gears changed so as to give the spreaders any desired speed of rotation.

The boxes 50 in which the shafts 40 and 26 are journaled, are secured directly against the faces of the sills 1, as shown clearly in Figs. 1 and 4, and consist of a cylindrical or tubular box or socket to receive the end of the shaft and a base or attaching plate extending laterally from the socket and provided with a plurality of openings through which bolts or rivets may be inserted into the sill. It will be readily noted that this construction permits the bearing to be very securely fastened to the sill while, at the same time, it permits the bearing to be very easily removed to permit repairs to be made to the shaft or to permit the substitution of a new shaft for a worn shaft. The boxes 51 in which the rear axle is journaled consist of sleeves passing under the sills and provided with lateral flanges 52 which bear against the under edges of the sills and are secured thereto by bolts 53 passing vertically entirely through the sills. A flange or plate 54 rises from the sleeve 51 and bears against the outer side of the sill and bolts 55 are inserted transversely through the said plate or flange and the sill. It will be noted that this construction is very strong and very effectually resists the great strain placed upon the machine at this point.

It is thought the operation and advantages of my improved apparatus will be readily understood and appreciated from the foregoing description, taken in connection with the accompanying drawings. The straw is loaded into the box or rack, consisting of the floor 9 and the sides 10, and the machine is then drawn over the field. When the machine has reached the point at

which it is desired to begin fertilizing, the clutch 18 is thrown into engagement with the sprocket hub 15 and the motion of the wheels 12 will be then transmitted to the 5 several working parts, the conveyer moving, as indicated by the arrows in Fig. 4, to carry the straw to and through the space between the uprights 35 and discharge the same onto the beaters. The beater shafts 10 will rotate in opposite directions, as indicated by the arrows in Fig. 2, and upon reference to said figure it will be readily noted that as the straw falls from the end of the conveyer it will descend directly upon 15 the beater arms and will be engaged by them so that it will be thrown rearwardly and laterally from the machine. The beater arms will rotate at a speed sufficient to throw the straw a considerable distance and 20 thereby thoroughly scatter it and prevent its dropping upon the ground in such masses as will prevent the rapid assimilation of the soil-enriching elements thereof by the ground. It will be readily noted that the 25 driving mechanism is very simple and direct acting. The machine may be manufactured at a low cost and will prove highly efficient when in use. It is not apt to get out of order and may, therefore, be very economically maintained.

Having thus described the invention, what is claimed as new is:

1. In a straw spreader, the combination of a truck having longitudinal sills, a box 35 resting on said sills and having a discharge opening in its rear end, a platform secured

upon and bridging the rear ends of the sills to receive material passing through said discharge opening, a frame secured upon and depending from said sills, standards in said frame between the sills, a shaft journaled upon said standards, means acting on said shaft to rotate the same, beater shafts mounted vertically in the frame between the standards and the respectively 40 adjacent sills and having their upper ends projecting above the platform and disposed at opposite sides of the discharge opening in the box, gearing operatively connecting said beater shafts with the first-mentioned 45 shaft, and radial beaters secured upon the upper ends of the said shafts and having their free ends describing paths extending into the path of material issuing from the discharge opening in the box. 50

2. In a straw spreader, the combination of a truck having rearwardly-projecting longitudinal sills, a supporting frame secured around and depending from the rear ends of said sills, beater shafts disposed vertically in said frame adjacent the respective sills, a shaft mounted horizontally in the frame between the beater shafts and operatively connected at its ends with said shafts, radial beater arms secured on the upper 65 ends of said beater shafts, and shredder teeth secured upon the beater arms to cut through straw delivered to the same, the free ends of the arms moving forwardly between the beater shafts. 70

In testimony whereof I affix my signature.
CHARLES L. BUEKER. [L. s.]
